UNITED STATES PATENT OFFICE

JOSEPH P. MURTAUGH, OF CHICAGO HEIGHTS, ILLINOIS, ASSIGNOR TO AMERICAN MANGANESE STEEL COMPANY, OF CHICAGO HEIGHTS, ILLINOIS, A CORPORATION OF MAINE

POWER ACTUATED DIPPER

Application filed August 26, 1931. Serial No. 559,433.

This invention relates to power actuated dippers, buckets and the like excavating implements and has among its important objects to provide an improved body assembly including an interchangeable lip member and renewable tooth structure.

The interchangeable lip assembly of the present case is allied in principle to the disclosure in application Serial No. 583,317 filed December 26, 1931, in both cases the purpose being to supply the user with a dipper body and a plurality of lip members so that the user may change the dipper body over, by interchange of lips, to meet different excavating requirements.

While the foregoing statement is indicative in a general way of the nature of the invention, other objects and advantages will be apparent upon a full understanding of the construction and cooperative relationship of the several parts of the implement.

One type of construction for reducing the invention to practice is presented herein by way of exemplification but it is to be understood that the invention is susceptible of embodiment in still other structurally modified forms without departing from the spirit of the invention, as defined by the subjoined claims.

In the accompanying one sheet of drawing—

Figure 1 is a view in side elevation of a dipper constructed in accordance with the present invention;

Figure 2 is a view in front elevation of a portion of the dipper;

Figure 3 is a view similar to Figure 1 but showing the lip and tooth assembly in section;

Figure 4 is a detail view in side elevation of the front portion of one of the side walls showing one form of anchoring means for an interchangeable lip member;

Figure 5 is a detail view in side elevation of a lip member;

Figure 6 is a similar view of a tooth, and

Figure 7 is a view in side elevation of a modified form of lip and tooth assembly.

Referring now to the drawing in detail, 50 represents the dipper body comprising a one

piece casting having integral front, side and back walls 6, 7 and 8 respectively.

The back wall 8 carries the usual lifting ear 9, the hinge bearings 10 and the stick bearings 11.

The lip member 12 is separately formed and comprises a cutting edge 13 made to accommodate separately formed interlocking teeth 14. The teeth for this purpose are made with integral jaws 15 and 16 (see Figs. 1, 3 and 6) which are adapted to straddle the cutting edge with a close clamping fit. The jaw 16 of each tooth is made with a continuation 17 which is passed through openings 18 made to receive them in the meeting flanges 19 and 20 on the lip and front wall respectively. After extending through these openings, rivets or some other double ended pin devices 21 suitable for the purpose are secured in the registering openings 22 and 23 to lock the jaws in place and at the same time mount the lip on the front wall of the body. The connection thus serves the dual purpose of locking the teeth to the lip and locking the lip with the teeth thereon to the front wall of the body. The flange 20 on the front wall is cast with pairs of reinforcing webs 24 which are spaced to fit the width of the continuations of the jaws 16 (see Fig. 2). This aids in holding the jaws in parallel alignment and adds rigidity to the structure.

The integral side members 25 of the lip are supported upon the edge of the side walls of the body and may be joined thereto by double ended pins or the like 26.

Referring to Figure 7, it will be seen that the teeth and lip may be either cast as an integral assembly or else separately formed and welded together. When this is resorted to the flange 19 on the lip need not be used; otherwise the assembly is effected as in the first form.

I claim:

1. A power actuated dipper comprising a body, a lip, teeth for said lip and means for anchoring the teeth to both the lip and body, comprising integral jaws for the teeth adapted to straddle the lip, an integral extension for one jaw of each tooth having an opening adjacent the end thereof, projecting flanges

on the body and lip having registering openings through which said integral extensions on the jaws project, and pin devices on the body seated in the openings in the extensions 5 of the jaws.

2. A lip and tooth assembly for power actuated dippers, comprising in combination, a cutting edge on the lip, teeth having jaws straddling said cutting edge, a flange on the 10 lip having a series of spaced openings therein and means on one jaw of each tooth projecting through said openings and providing means for securing the lip and tooth assembly to the body of the dipper of the class 15 described.

3. A lip and tooth assembly for power actuated dippers, comprising in combination, a cutting edge on the lip, teeth having jaws straddling said cutting edge, a flange on the 20 lip having a series of spaced openings therein and means on one jaw of each tooth projecting through said openings and providing means for joining the teeth to the lip.

4. A power actuated dipper embodying in 25 its construction a body providing front and side walls, a flange formed on the upper edge of the front wall having openings therein, reinforcing ribs on the front wall merging with said flange, a separately formed lip for 30 said body, a flange on said lip adapted to bear against the flange on the front wall of the body and having openings therein adapted to register with openings in said first named flange, teeth for said lip having jaws adapted 35 to straddle the lip, an extension on one jaw of each tooth adapted to project through the registering openings in said flanges and seat between the reinforcing ribs on the front wall of the body.

40 5. A power actuated dipper comprising a body, a lip, teeth for said lip and means for anchoring the teeth to both the lip and body, comprising integral jaws for the teeth adapted to straddle the lip, an integral extension for one jaw of each tooth, projecting flanges on the body and lip having registering openings through which said integral extensions on said jaws project, and means for securing said extensions to said body.

45 6. A power actuated dipper embodying in its construction a body providing front and side walls, a flange formed on the upper edge of the front wall having openings therein, reinforcing ribs on the front wall merging 50 with said flange, a lip for said body formed separately therefrom, teeth for said lip having jaws adapted to straddle the lip, an extension on one jaw of each tooth adapted to project through one of said openings in 55 said flange and seat between two of the reinforcing ribs on the front wall of the body.

60 7. A power actuated dipper embodying in its construction a body providing front and side walls, a flange formed on the upper edge 65 of the front wall having openings therein, re-

inforcing ribs on the front wall merging with said flange, a lip for said body formed separately therefrom, teeth for said lip and formed integrally therewith having jaws integrally straddling the lip, an extension on 70 one jaw of each tooth adapted to project through one of said openings in said flange and seat between two of the reinforcing ribs on the front wall of the body.

8. In an excavating dipper, a dipper front 75 wall, a digging lip member adapted for detachable securement to said front wall, said lip including a plurality of integral tongue-like extensions rearwardly extending therefrom, said front wall including a flanged forward edge provided with a plurality of openings adapted to receive said extensions of said lip and means for fastening said extensions to said front wall rearwardly of 80 said flanged edge.

Signed at Chicago, Illinois, this 18th day of August, 1931.

JOSEPH P. MURTAUGH.
